UNITED STATES PATENT OFFICE.

ROBERT N. COOK, OF ASPINWALL, PENNSYLVANIA.

RELEASING-CRANK MECHANISM FOR INTERNAL-COMBUSTION ENGINES.

1,348,931.

Specification of Letters Patent. Patented Aug. 10, 1920.

Application filed May 24, 1919. Serial No. 299,577.

To all whom it may concern:

Be it known that I, ROBERT N. COOK, a citizen of the United States, residing at Aspinwall, in the county of Allegheny and 5 State of Pennsylvania, have invented certain new and useful Improvements in Releasing-Crank Mechanism for Internal-Combustion Engines, of which the following is a specification.

10 My invention consists in an improvement in ratchet controlled cranking mechanism for cranking the shaft of an internal combustion engine, and particularly as to the application thereof to the engine of an automobile. It has for its object to overcome the usually present danger and risk of a 15 sudden reverse movement of the crank due to "back-firing," whereby to render the cranking operation safe. Back firing, as is well known, is usually due to the somewhat premature explosion of the charge before the 20 crank of the particular connecting rod and piston involved has passed over the dead center, and is ordinarily due to too early 25 sparking.

In my invention I provide means for automatically disengaging a crank from the shaft actuating mechanism, whether it be the actual engine shaft itself or a supplemental removable shaft coupled therewith.

30 In the drawings which show one preferred embodiment of the invention,

Figure 1 is a plan view of the device as applied to the engine shaft in position for 35 operation;

Fig. 2 is a view of the device in front elevation, partly broken away, on the line II, II of Fig. 1;

Fig. 3 is a sectional view on the line III, 40 III of Fig. 1; and

Fig. 4 is a perspective detail view of the plate holding socket for the locking pawl plate.

Fig. 5 is a sectional detail of pawl and 45 locking pin.

The invention may be incorporated fixedly with the end of the engine shaft or with a removable clutching socket adapted to engage the shaft and to be removed therefrom with the crank and its parts when not in use. The drawings show the latter form. In these, a clutch socket 2 of common form is adapted to be telescoped over the end of engine shaft 3 and to engage the clutch 4 thereof by the usual clutch terminal 5.

Socket 2 is provided with a short ex-

tended shaft 6 upon which is journaled a pawl-holding plate 7 adapted to be thrust into temporary socketed engagement with the holding lugs 8 of a socket plate 9. Said 60 socket plate is secured to the frame of the engine or to the front of an automobile frame by screws or bolts through holes 10 and is provided with a hole 11 through which passes the short shaft extension 6 for 65 rotation therein, as shown in Fig. 1. A ratchet wheel 12 and a fixedly connected or integral cam wheel 13 are freely journaled on the same shaft 6 outwardly beyond the plate 7, the ratchet wheel lying 70 directly against the plate and in line with the pawl 14 therefor. Said pawl is pivoted to the plate 7 at 15 and has a suitable spring 16 to hold the pawl in locking engagement with the ratchet wheel 12 when it is reversed, 75 but permitting its free rotation away from and under the pawl.

Crank 17 is freely journaled on the end of shaft 6 and may be moved backwardly without interference. A ratchet wheel 18 is secured to the shaft by pin 19 or otherwise, and in line therewith is a co-acting pawl 20 pivoted at 21 to the crank in any suitable mounting, as shown. A spring 22 normally holds the pawl in engagement with ratchet 85 wheel 18 so that the crank may impart turning movement to the shaft, when turned forwardly.

Cam wheel 13 is provided with an annular series of abrupt cam lugs 23 and alternating 90 concave recesses 24 adapted to receive and engage the bearing lug 25 of pawl 20 and the pivoted roller 26 thereof.

Pawl 20 is provided with a socket 27 adapted to be engaged by the end of locking 95 pin 28 having a seating spring 29 when the pawl is raised to register with socket 27 by riding up backwardly over lug 23, out of engagement with ratchet wheel 18. By this means the pawl is temporarily held upwardly out of operation, until again released. The pin is provided with a shank and terminal button 30 so that it may be withdrawn to allow the pawl to assume operative engagement with the ratchet wheel by action 100 of spring 22.

In cranking, with the pawl 20 engaging ratchet wheel 18, shaft 6 and socket 2 are rotated in the usual manner, and cam wheel 13 will be carried around freely on shaft 6 110 by roller 26 and lug 25, fitting in recess 24. In case of back fire, however, reverse move-

ment of shaft 6 and ratchet wheel 18 will tend to reverse the crank movement through pawl 20. Pawl 14, however, locks ratchet wheel 12 against reverse movement, also holding cam wheel 13 at the same time, so that it is stationary as to pawl 20. Upon reverse movement of the crank therefore, roller 26 and lug 25 will at once ride upwardly on the next rearwardly adjacent lug 23, immediately withdrawing the outer end of pawl from the engaged tooth of ratchet wheel 18 and immediately releasing the crank from reverse action of the shaft.

The construction and operation of the invention will be readily understood and appreciated by those skilled in the art. It entirely obviates the danger of accidental reverse movement of the engine shaft and crank, and renders the operation of cranking entirely safe, and independent of any harmful results upon back firing.

What I claim is:

1. In combination with a power driven shaft subject to sudden reversal, a fixedly attached ratchet wheel, a loosely mounted cam wheel having a controlling ratchet wheel and a pawl therefor, and a crank having a pawl engaging the fixedly attached ratchet wheel and the cam wheel respectively.

2. In combination with a power driven shaft subject to sudden reversal, a fixedly attached ratchet wheel, a loosely mounted cam wheel having a controlling ratchet wheel and a pawl therefor, and a crank having a pawl engaging the fixedly attached ratchet wheel and having a portion adapted to ride upon and be retracted by the cam wheel.

3. In combination with a power driven shaft subject to sudden reversal, a ratchet wheel fixedly attached to the shaft, a cam wheel loosely mounted on the shaft having a co-acting loosely mounted ratchet wheel, a spring pressed pivoted pawl for said ratchet wheel, and a crank loosely journaled on the shaft provided with a spring pressed pivoted pawl engaging the fixedly attached ratchet wheel and provided with a portion adapted to ride upon and be retracted by the cam wheel.

4. In combination with a power driven shaft subject to sudden reversal, a ratchet wheel fixedly attached to the shaft, a cam wheel loosely mounted on the shaft having a co-acting loosely mounted ratchet wheel, a spring pressed pivoted pawl for said ratchet wheel, and a crank loosely journaled on the shaft provided with a spring pressed pivoted pawl engaging the fixedly attached ratchet wheel and provided with a lug and roller adapted to ride upon and be retracted by the relatively stationary cam wheel when the crank and pawl are suddenly reversed by the fixedly attached ratchet wheel.

5. In combination with a power driven shaft subject to sudden reversal, a fixedly attached ratchet wheel, a loosely mounted cam wheel having a controlling ratchet wheel and a pawl therefor, and a crank having a pawl engaging the fixedly attached ratchet wheel and provided with a lug and roller adapted to ride upon and be retracted by the stationary cam wheel when the crank and pawl are suddenly reversed by the fixedly attached ratchet wheel.

6. In combination with a power driven shaft subject to sudden reversal, a fixedly attached ratchet wheel, a loosely mounted cam wheel having a controlling ratchet wheel and a pawl therefor, a crank having a pawl engaging the fixedly attached ratchet wheel and the cam wheel respectively, and a latch device mounted in the crank adapted to engage the pawl when it is retracted by reverse movement with respect to the cam wheel to hold it away therefrom.

7. In combination with a cranking shaft having a fixedly attached ratchet wheel, a rotatably mounted cam and its holding ratchet wheel, and a loosely mounted crank having a spring pressed pawl for the fixedly attached ratchet wheel provided with an abutment roller for the cam wheel; a pivoted spring pressed pawl engaging the holding ratchet wheel of the cam.

8. In combination with a cranking shaft having a fixedly attached ratchet wheel, a rotatably mounted cam and its holding ratchet wheel, and a loosely mounted crank having a spring pressed pawl for the fixedly attached ratchet wheel provided with an abutment roller for the cam wheel; a pivoted spring pressed pawl engaging the holding ratchet wheel of the cam, a mounting plate for said pawl, and means for holding the same in operative position.

9. Safety cranking mechanism consisting of a clutch having a stud shaft provided with a fixedly attached ratchet wheel, a cam wheel and a controlling ratchet wheel connected therewith rotatably mounted on the shaft, a crank loosely mounted on the shaft having a spring-pressed pivoted pawl for the fixedly attached ratchet wheel provided with an abutment roller for the cam wheel, and a stationary pivoted spring-pressed pawl engaging the cam wheel controlling ratchet wheel.

10. Safety cranking mechanism consisting of a clutch having a stud shaft provided with a fixedly attached ratchet wheel, a cam wheel and a controlling ratchet wheel connected therewith rotatably mounted on the shaft, a crank loosely mounted on the shaft having a spring-pressed pivoted pawl for the fixedly attached ratchet wheel provided with an abutment roller for the cam wheel, a stationary pivoted spring-pressed pawl engaging the cam wheel controlling ratchet wheel.

wheel, a mounting plate therefor, and a holder for said plate.

11. In combination with a removable cranking device for internal combustion engines embodying a clutch and its shaft having a crank and co-acting engaging and releasing ratchet mechanism and a cam there-

for; a fixedly mounted socket plate and a pawl supporting holder removably mounted therein having a spring-pressed locking 10 pawl for one of said ratchet wheels.

In testimony whereof I hereunto affix my signature.

ROBERT N. COOK.
